UNITED STATES PATENT OFFICE.

WILLIAM W. RODGERS, OF BALTIMORE, MARYLAND, ASSIGNOR TO WILLIAM W. RODGERS, WILLIAM J. SHAMBERGER, AND ROBERT L. SHAMBERGER, TRUSTEES, OF BALTIMORE, MARYLAND.

REPLACEABLE HEEL.

Application filed May 24, 1926. Serial No. 111,213.

My invention relates to improvements in heels for shoes, one object of my invention being to provide a heel both easily attachable and detachable and which at the same time is retained firmly in place when attached under normal conditions.

A further object of my invention is the providing of means for associating the heel and tread whereby relative lateral or turning movement will be prevented.

A further object of my invention is the providing of a heel retaining device which may be manipulated for the purpose of applying or removing a heel without the exercise of skill, it being my purpose to produce heels having attaching means which anyone may apply and remove without special appliances.

A further object of my invention is the providing of a heel-fastening one member of which is embedded in the material at the time the heel is made and from which the member cannot with ordinary use be disconnected.

A further object of my invention is the providing an improved fastening formed integral with the heel, flexible in character and formed with an initial shape in reverse to that imparted in attaching whereby there is an additional tendency to remain tight and immovable.

A further object of my invention is the providing a rather rigid member to the shoe being provided with substantially a continuous edge for securing purposes, and providing in the heel a very flexible conjugate member to fit over the member secured to the shoe.

With the foregoing and other objects in view, my invention consists of the novel construction, combination and arrangement of parts as hereinafter specifically described and illustrated in the accompanying drawings, wherein is shown the preferred embodiment of my invention, but it is understood that changes, variations and modifications may be resorted to which come within the scope of the claims hereunto appended.

In the drawings of the herein-described embodiment of my invention, Figure 1 is an inverted plan view of the heel portion of the shoe to which the heel is to be attached

and having in place the male member secured thereto by screws, nails or other suitable fastenings; Fig. 2 is a plan view of the heel showing the securing appliance formed of metal; Fig. 3 is an inverted sectional view in elevation, taken through 3-3 of Fig. 1; Fig. 4 is an inverted sectional view taken through 4-4 of Fig. 2; Fig. 5 is an enlarged sectional view of the heel portion of the shoe with the fastener attached and the heel placed thereon as in use; in other words, it is a combination of the parts shown in Figs. 3 and 4; Fig. 6 is an enlarged sectional view in elevation similar to that shown in Fig. 5, with the heel bent as being applied to the heel portion of the shoe; and Fig. 7 is a view of a shoe to which my improved heel has been applied.

Similar numerals refer to similar parts throughout the several views.

1 is the shoe. 2 the heel portion of the shoe. 3 is the shoe member of the attaching device, and is secured to the shoe by means of screws, nails or other suitable appliances 4.

5 is the heel in which is embedded, or molded therein, heel member 6. This member, when used in rubber heels, is preferably shaped as shown in Figs. 2 and 4 so that it may be easily vulcanized in and secured to and within the heel 5. This member is provided or made spring-like throughout its various portions, and is provided with numerous turned-in ends 7 to lock within the rubber heel. These ends are formed with a spring-clamping portion 8 which fits over the edge 9 of the shoe member 3, clamping and locking over the same.

Heel member 6 is provided in one portion, preferably in the rear, with locking member 10 fitting into its conjugate member 11, which guards against any tendency to rotation.

Referring to Fig. 4, which shows a section of the heel in normal condition before attaching to the shoe, it will be noticed that the same is convexed, whereas the same heel in being attached, as shown in Fig. 6, is concave. This normal convexity tends to maintain a tight fit when the heel is attached to the shoe.

Referring to Fig. 5, it will be noticed that the interior of shoe member 3 forms a space between it and heel member 6. This space

permits of a cushioning action of the heel over the same and is utilized in the attaching and detaching operation, as shown in Fig. 6.

The operation of my invention is as follows:

5 The shoe, having shoe member 3 attached thereto and the heel being formed as above described, the heel is placed on the shoe with locking member 10 in conjugate member 11 and is bent backwards from the front end and concaved sideways, as shown in Fig. 6, until heel member 6 clamps over shoe member 3, when the securing is completed.

10 Having thus described my invention, what I claim and desire to secure by Letters Patent is:

15 1. A replaceable shoe heel provided with an attaching triangular member provided with an exterior flange undercut and substantially continuous in extent, a resilient tread member provided with a recess and having secured in said recess a metallic, resilient triangular attaching member provided with conjugate flange projections co-operating with the first mentioned attaching member on the exterior thereof so that they are secured together by first a relatively sliding movement longitudinally, then snapping the parts together.

20 2. A replaceable shoe heel provided with

an attaching member provided with exterior projections, a resilient tread member provided with a recess and having secured in said recess a metallic resilient attaching member provided with conjugate projections co-operating with the first mentioned attaching member on the exterior thereof so that they are secured together by first, a relatively sliding movement longitudinally, then snapping the parts together.

25 3. A replaceable shoe heel comprising, a metallic male shoe member for attaching to a heel of a shoe provided with substantially a continuous outwardly extending edge flange and practically rigid in construction, a flexible heel lift and an inwardly extending metal flexible female heel member attached to said heel for locking over said shoe member by sliding over opposite edges thereof and finally catching over said flange.

40 4. In a detachable shoe heel as claimed in claim 2, the female attaching member attached to said heel consisting of a plurality of projecting prongs formed near their extremity into a flange or projection conjugate with said first attaching member, then continuing and formed to bed within said heel for securing purposes.

45 WILLIAM W. RODGERS.
